CONTAINER

Norberta C. R. Azpiazu, Habana, Cuba

Application April 15, 1943, Serial No. 483,204
In Cuba June 17, 1942

1 Claim. (Cl. 222—390)

My invention relates to the packaging of shaving creams, tooth paste, cosmetics and the like, and has among its objects and advantages the provision of an improved dispensing container of the noncollapsible type.

In the accompanying drawing:

Figure 1 is a face view of the container.

Figure 2 is a longitudinal sectional view.

Figure 3 is a sectional view along the line 3—3 of Figure 2.

Figure 4 is a face view of a turning knob.

Figure 5 is a sectional view of a group of co-acting parts, and

Figure 6 is a perspective view of a plug placing and removing key.

In the embodiment of the invention selected for illustration, the container 10 comprises a glass or plastic tubular body 12 having an extruding neck 14 externally threaded for threaded connection with a closure cap 16. The contents of the container are extruded through the medium of a glass or plastic piston 18, the latter being threadedly connected with a screw 20 positioned concentrically with the body 12.

In the end of the body 12 opposite the neck 14 is threadedly inserted a plug 22 constituting a bottom for the body. This plug is provided with a bore 24 in its inner face for reception of a flange 26 formed as an integral part with the screw 20. This flange is provided with an annular and tapered face 28' engaging the correspondingly shaped bottom face 30 of the bore 24. The screw 20 is extended beyond the flange 26 to serve as a mount for a turning knob 32.

The screw end 34 extends loosely through the small bore 36 in the plug 22, and the end 34 is threaded tightly in the bore 38 in the knob 32 as far as it will go, with the knob having face engagement with the end of the body 12 to restrain the screw 20 from relative axial movement and to hold the face 28' in sealing engagement with the face 30. However, the screw 20 may easily

rotate through the medium of the knob 32 for imparting axial movement to the piston 18, as when extruding material through the neck 14.

In view of the fact that the plug 22 fits flush with the body 12, this body is provided with two recesses 40 for the reception of the pins 42 of a key 44. These pins are insertable through bores 46 in the knob 32 so that access may be had to the plug 22 notwithstanding the fact that the knob 32 overlies the plug. Thus the plug 22 may be easily removed for replenishing purposes.

Without further elaboration, the foregoing will so fully explain my invention, that others may, by applying current knowledge, readily adapt the same for use under various conditions of service.

I claim:

A dispensing device of the character described comprising a tubular body having an extruding opening at one end and interiorly screw threaded 20 at its opposite end, a screw mounted axially in said body, an annular tapered flange formed on the screw adjacent one end, an exteriorly threaded plug fitted in the threaded end of the body, said plug having an axial bore therethrough 25 loosely receiving the screw therethrough and an enlarged tapered bore in the inner end in which the tapered flange is rotatably seated, a knob mounted against the outer end of the body and plug having a threaded axial bore opening 30 through the inner end and terminating short of the outer end, the bore in the knob threadedly engaging an end portion of the screw, and a piston fitted for axial sliding movement in the body having an axial through bore threadedly engag- 35 ing the screw, the knob being provided with a pair of through bores parallel with and spaced from the axial bore and the plug being provided with bores opening through the outer end adapted to align with the pair of bores in the knob 40 for the insertion of a key to position the plug in the body.

NORBERTA C. R. AZPIAZU.
